Patented Dec. 2, 1913.

UNITED STATES PATENT OFFICE.

WILLIAM ADAMS, OF SAN FRANCISCO, CALIFORNIA.

CHANDELIER.

1,080,093.

Specification of Letters Patent.

Patented Dec. 2, 1913.

Application filed February 24, 1913. Serial No. 750,098.

To all whom it may concern:

Be it known that I, WILLIAM ADAMS, a citizen of the United States, residing in the city and county of San Francisco and State 5 of California, have invented certain new and useful Improvements in Chandeliers, of which the following is a specification.

My invention relates to that class of chandeliers in which the lighting unit and its 10 associated ray-directing means are adapted to be turned for direct or indirect lighting, that is, to direct the light either downward or upward.

My invention is particularly applicable to 15 that type of chandeliers having a single lighting source, or a group thereof so closely juxtaposed as to be in effect a unit, and which may, therefore, be termed a unit type of chandelier in general contradistinction to 20 a cluster type, such, for example, as those having a plurality of independent arms or branches. In chandeliers of this type in which the body structure carrying the lighting unit and its associated shade or ray-directing means is pivotally suspended by 25 hanger-arms adapting these parts to be reversed, a somewhat simple problem is presented, where only two oppositely located hanger-arms are employed, for the body 30 structure may in such case be swung up or down between said arms. But where it is desirable that more than two hanger-arms be employed, as, for example, for the sake 35 of proportional design in heavy fixtures, some means must be devised for getting such additional arms out of the way, in order to permit the swinging movement of the body structure between the two opposite arms from which it is pivotally suspended. 40 The object of my invention is to provide for this result, and to this end my invention consists in the novel constructions and arrangements which I shall now fully describe by reference to the accompanying drawings, 45 in which:—

Figure 1 is an elevation of my chandelier. Fig. 2 is a top plan view taken from below the canopy. Fig. 3 is a sectional detail, enlarged, showing the connection of three of 50 the hanger arms with the poly-branch hanger-head. Fig. 4 is a similar detail, showing the pivotal connection at the upper end of the fourth hanger arm. Fig. 5 is a detail section showing the pivotal connection 55 of the lower ends of two of the hanger arms with the body shell. Fig. 6 is a detail sec-

tion showing the detachable connection of the lower ends of the other two hanger arms.

1 is the canopy and 2 is the stem of the chandelier. To the lower end of this stem 60 is fitted the poly-branch hanger head 3. In its best construction it has four symmetrical and equidistant branches, designated by 4, 5, 6 and 7, which carry the hanger arms 8, 9, 10 and 11 respectively. Three of these 65 branches 4, 5 and 6 are connected with and carry their hanger arms 8, 9, and 10 respectively by some suitable form of permanent attachment. That shown in Fig. 3 is a good construction. It consists of an ornamental 70 knob 12 screwed to the end of the branch. In the top of this knob is screwed an ornament 13, and into its lower face is screwed the upper end of the hanger arm. The fourth branch 7 carries its hanger arm 11 75 by a pivotal connection of some suitable character which permits said hanger arm to swing laterally. This connection is shown in Fig. 4 in which 12' is an ornamental knob similar in general respects to the knobs 12 80 and carrying the ornament 13' and the hanger arm 11 in the same manner. But said knob 12' has a reduced portion 14 which is rotatably mounted or journaled in the branch 7 and is held therein by a stud 15 in 85 the branch entering a circumferential groove 16 in the reduced portion 14.

The body-shell is of suitable character. It is here shown as comprising a top band 17, frame arms 18 and a bottom holder 19. 90 This shell carries the lighting unit or lamp 20, and the ray-directing means or shade 21, in the accepted manner. The shell is pivotally connected with the lower extremities of two opposing hanger arms, namely 8 95 and 10. The pivotal connection is best made as shown in Fig. 5. The lower ends of the hanger arms 8 and 10 screw into fittings 22, each of which at its inner end is tapped with a short nipple 23. The body band 17 100 is pivoted on this nipple and is held against the fitting by a nut 24 on the inner end of the nipple. The body shell is detachably connected with the other two hanger arms 11 and 9 by some suitable connection. That 105 shown in Fig. 6 is deemed the best. The lower ends of the hanger arms 11 and 9 are screwed into fittings 25, the inner ends of which bear against the body band 17. On the inside of the band, which is quite thin, 110 is secured a reinforcing piece 26 thick enough for an internal thread to receive the

threaded end of a screw-pin 27 which passes through the fitting 25 and thus holds said fitting to the band. The head of the pin 27 is ornamental to resemble the ornament of 5 the other fittings 22, so that the design is uniform.

The operation is as follows: Suppose the body-shell be in the position shown in full lines in Fig. 1 in which the light rays are 10 directed upward for indirect lighting. In this position the body-shell is suspended by all four hanger arms, and is locked in this position against swinging movement, because, though its pivotal centers are free, the 15 hanger arms 9 and 11 are in its path of movement and moreover are secured to it. Now, in order to reverse the light, both hanger arms 9 and 11, are released from the body shell band 17, by unscrewing the pins 20 27. Then the hanger arm 11 is swung sideways on its pivotal connection at its upper end, to a position out of the way, as is indicated in dotted lines in Fig. 1. Thereupon the body shell with its light unit and ray- 25 directing means is swung upward away from the released but still positioned hanger arm 9, and between the pivot suspending hanger arms 8 and 10 to a reversed position as shown by the dotted lines in Fig. 1, so 30 that the parts are then in position for direct lighting. In this position the hanger arm 9 acts as a stop to limit the reversal of the parts, for the body shell will at said limit come in contact with it. Finally, to lock 35 the parts in this reversed position, the hanger arm 11 is swung sidewise back to its normal place, and then both hanger arms 9 and 11 are again secured to the body band 17 by screwing in the pins 27. The screw 40 pin holes in the body band are, of course, reversed, for the band is reversed, but as their location is symmetrical, the pins 27 readily engage them.

I claim:—

45 1. In a chandelier, the combination of a stem-structure; an annular series of hanger-arms depending therefrom, said series comprising plural pairs, the members of which are oppositely located; a body shell; a pivotal connection at opposite sides of the body shell with the lower extremities of a first pair of hanger arms; a fixed connection between the upper ends of said first pair of hanger arms and the stem-structure and also 50 55 between the upper end of one member of a second pair of hanger arms and said stem-structure; a pivotal connection between said stem-structure and the upper end of the other member of said second pair of hanger arms adapted to permit said hanger arm to 60 swing laterally out of the path of the movement of the body-shell on its pivotal connections with the first pair of hanger-arms; a detachable connection between said body shell and the lower extremities of said sec- 65

ond pair of hanger arms; a source of light carried by the body shell; and ray-directing means associated with said source of light.

2. In a chandelier, the combination of a stem; a symmetrical four branched head 70 carried by the stem; a first pair of opposing hanger arms having at their upper ends a fixed connection with two opposing branches of said head; a second pair of opposing hanger arms, one of which has at its upper 75 end a fixed connection with one of the other branches of said head, the other arm of said second pair having a pivotal connection at its upper end with the remaining branch of said head, adapting said arm to swing laterally; a body-shell; a pivotal connection between the body-shell and the lower ends of the first pair of arms; a detachable connection between said body shell and the lower ends of the second pair of arms; a source 80 of light carried by the body-shell; and ray-directing means associated with said source of light.

3. In a chandelier, the combination of a stem; a symmetrical four branched head 90 carried by the stem; a first pair of opposing hanger arms having at their upper ends a fixed connection with two opposing branches of said head; a second pair of opposing hanger arms, one of which has at its upper 95 end a fixed connection with one of the other branches of said head, the other arm of said second pair being pivotally mounted at its upper end within the remaining branch of said head, adapting said arm to swing laterally; means for holding said arm in said branch; a body-shell; a pivotal connection between the body-shell and the lower ends of the first pair of arms; a detachable connection between said body shell and the 100 lower ends of the second pair of arms; a source of light carried by the body-shell; and ray-directing means associated with said source of light.

4. In a chandelier, the combination of a 110 stem; a symmetrical four branched head carried by the stem; a first pair of opposing hanger arms having at their upper ends a fixed connection with two opposing branches of said head; a second pair of opposing 115 hanger arms, one of which has at its upper end a fixed connection with one of the other branches of said head, the other arm of said second pair having a pivotal connection at its upper end with the remaining branch of said head, adapting said arm to swing laterally; a body-shell; a pivotal connection between the body-shell and the lower ends of the first pair of arms; a detachable connection between said body shell and the lower 120 ends of the second pair of arms, consisting of screw pins passing through the arms and threaded in the body shell; a source of light carried by the body-shell; and ray-directing means associated with said source of light. 125

5. In a chandelier, the combination of a stem; a symmetrical four branched head carried by the stem; a first pair of opposing hanger arms having at their upper ends a fixed connection with two opposing branches of said head; a second pair of opposing hanger arms, one of which has at its upper end a fixed connection with one of the other branches of said head, the other arm of said 10 second pair being pivotally mounted at its upper end within the remaining branch of said head, adapting said arm to swing laterally; means for holding said arm in said branch; a body-shell; a pivotal connection 15 between the body-shell and the lower ends of the first pair of arms; a detachable connection between said body shell and the lower ends of the second pair of arms, consisting of screw pins passing through the arms and threaded in the body-shell; a 20 source of light carried by the body-shell; and ray-directing means associated with said source of light.

In testimony whereof I have signed my name to this specification in the presence 25 of two subscribing witnesses.

WILLIAM ADAMS.
